[57] CLAIM

The ornamental design for handle for kitchen tools or
the like, as shown and described.

DESCRIPTION

FIG. 1 is a top plan view of a handle for kitchen tools or
the like, showing my new design, the bottom plan view
being a mirror image thereof;

FIG. 2 is a right side elevational view thereof, the left
side being a mirror image thereof;

FIG. 3 is a rear end elevational view thereof;

FIG. 4 is a front end elevational view thereof; and

FIG. 5 is a cross-sectional view thereof, taken on line
5—5 of FIG. 1.

FIG. 1

FIG. 2

FIG. 5

FIG. 3

FIG. 4
